CLAIM

The ornamental design for an electrical connector, as shown and described.

DESCRIPTION

FIG. 1 is a front, bottom, and right side perspective view of an electrical connector showing our new design; FIG. 2 is a rear, bottom, and right side perspectives view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a cross-sectional view thereof, taken along line 9-9 of FIG. 3; and,

FIG. 10 is a view thereof, taken from the direction of arrow 10 of FIG. 8.

(Continued)

The broken lines shown in the drawings are included for the purpose of illustrating unclaimed environment only, and form no part of the claimed design.
